Patented Feb. 28, 1922.

UNITED STATES PATENT OFFICE.

HENRY J. MARK, OF ST. LOUIS, MISSOURI.

PLASTERING LATH.

1,408,217.

Specification of Letters Patent. Patented Feb. 28, 1922.

Application filed November 24, 1920. Serial No. 426,161.

To all whom it may concern:

Be it known that I, HENRY J. MARK, a citizen of the United States, residing at St. Louis, State of Missouri, have invented certain new and useful Improvements in Plastering Laths, of which the following is a full, clear, and exact description, reference being had to the accompanying drawings, forming a part hereof.

10 The present invention is directed to improvements in plastering laths, the object sought being to provide a lath in sheet form that may be quickly applied to the studs to which the lath is nailed, said sheet comprising a plurality of corrugated veneer strips with plane backings and of a length equal to the distance between the centers of adjacent studs, the strips being spaced uniformly apart and connected together by 15 means of a wire to make the sheet flexible, the sheet being preferably limited to four, five, or six foot lengths. The advantages of a sheet lath as here outlined over the usual construction of lath are (1) the saving of material; (2) a lighter lath; (3) the lath is quickly applied; (4) it forms a more effective anchor for the plaster; (5) it permits of a free circulation of air, thereby making the plaster quick-drying; (6) it 20 ensures a permanently dry coat of plaster; (7) it is an effective sound deadener; (8) it can be applied by the unskilled laborer; (9) it requires no hair as a binder for the plaster; (10) it permits the use of inexpensive plaster and of a thinner layer of plaster; and finally, the invention presents further and other advantages more fully apparent from the following detailed description in connection with the accompanying drawings 25 in which—

Figure 1 represents an elevation of a section of a partition wall showing one form of my invention applied thereto; Fig. 2 is a vertical cross-section on the line 2—2 of Fig. 1; Fig. 3 is a section similar to Fig. 2 but on a larger scale; Fig. 4 is a perspective of a small section of a lath sheet; and Fig. 5 is a cross-section of a lath showing a slight modification.

50 Referring to the drawings, and for the present to Figs. 1 to 4 inclusive, S, represents the usual studs to which laths are nailed, as well understood in the art. The improved lath comprises an inner plane veneer strip 1 and outer corrugated veneer strips 2, the individual laths being spaced apart a distance not exceeding one-quarter of an inch; one-eighth of an inch being in the majority of cases sufficient. The laths are 55 flexibly connected and held together by two rows of a wire binder, said binder comprising a pair of wires *w* passed over the opposite faces of the laths and twisted in the key spaces *a* between the laths, the whole forming a flexible lath sheet that may be quickly 60 nailed to the studs. The wrapping of the wire around the lath members and the twisting of the same along the edges of the laths is preferably done by machinery. These wire binding machines are well known in 65 the art, and there is no necessity to describe the operation of such a machine in the present connection. In the prevailing constructions of laths the laths are generally spaced at least one-half inch apart so as to provide a firm "key" for the plaster. Such a key necessarily entails the consumption of a maximum quantity of plaster, and considerable plaster too is wasted on account of excessive extrusion thereof through the spaces 70 between the laths by the pressure of the trowel applied thereto, the plaster falling behind the laths into the spaces between the studs. With my invention excessive spacing between the laths for keying the plaster is 75 unnecessary for the reason that the corrugations of the outer veneer strip 2 to which the plaster *P* is applied serve as keys for the plaster, this keying being enhanced by cutting the veneer strips so as to cause the corrugations to be disposed at an incline to the longitudinal edges of the strip, this incline being substantially at an angle of from five to ten degrees to the edge of the strip. With a plane lath as ordinarily constructed not 80 only is a thick key necessary but a thick layer of plastering is required so as to hold together, both of these objections being avoided by my invention. With the use of a corrugated lath as described a layer of 85 plaster not in excess of one-quarter inch has been found ample in practice, the comparatively narrow spaces *a* between the laths and the inclined corrugations serving as ideal means of anchoring or keying the plastering to the laths. Obviously the corrugations of the outer strips 2 form air passages 90 *h* with the inner plane strips 1, these air passages permitting air to freely circulate behind the coat of plastering, and not only 95 operating to hasten the drying of the coat, but ensuring a permanently dry coat after 100 105 110

the same has once thoroughly dried. In applying the lathing, the lath sheet is first tacked at two or more points to the studding so as to ensure the exact position therefor, 5 after which the laths may be quickly nailed to the studs as clearly obvious from the drawings. By reducing the spacing a between the individual laths, very little plaster will be wasted, the key formed by the space 10 a holding together and not readily dropping off the main body of plaster as a result of excessive extrusion under the pressure of the trowel.

In the form of lath above described, I apply a corrugated strip 2 to each face of the plane strip 1; but by way of modification I may dispense with one of the corrugated strips as shown in Fig. 5, the lath comprising a single corrugated strip 2 with a backing 20 of a plane veneer strip 1. In the latter case the plane strip is directly applied to the studding S. Of course, whether I dispense a corrugated strip on one or both sides of the plane strip, the latter will always 25 form a backing for the corrugated strip. With two outer corrugated strips and an inner plane strip I secure a stronger or stiffer lath, the same having three thicknesses of veneer as compared with two thicknesses where one of the corrugated strips 30

is dispensed with. While I preferably employ wood veneer, I may use paper or other suitable material. Referring to Fig. 3, it will be observed that the wire w spans the depressions between the ridges of the corrugations, allowing the plaster which is applied to the lath to lodge behind the wire in the depressions. In this way, the wire serves not only as an additional anchor for the plaster, but operates as a reinforcing 35 member therefor.

Having described my invention what I claim is:

A plastering lath sheet comprising a succession of parallel laths spaced apart, each 45 lath comprising an inner plane veneer backing strip and outer bounding corrugated veneer strips with corrugations disposed at an angle to the longitudinal edges of the lath, and a plurality of parallel wire binders 50 disposed across the laths and wrapped around the successive laths and jointedly coupling the same to one another, the whole forming a flexible sheet.

In testimony whereof I affix my signature, 55 in presence of two witnesses.

HENRY J. MARK.
